VANITY CASE

Filed Sept. 2, 1927

UNITED STATES PATENT OFFICE.

WALTER PORANSKI, OF CHICAGO, ILLINOIS, ASSIGNOR TO JOSEPH BAER, OF NEW YORK, N. Y.

VANITY CASE.

Application filed September 2, 1927. Serial No. 217,273.

My present invention relates to vanities, that is, to toilet kits of the type preferably embodying face powder, a mirror and a powder puff, and aims to devise articles of the general character specified which are simple in construction, which may be readily and conveniently fabricated and assembled, which may be economically manufactured, and which, in their construction, 10 assembly and use, provide many conveniences and superiorities over the articles hitherto employed in the art for the same general purposes. Other objects and advantages of the present invention will in 15 part be pointed out in detail hereinafter and will in part be obvious to those skilled in the art to which the present invention relates.

In the accompanying specification I shall describe and in the annexed drawing show, 20 an illustrative embodiment of the present invention. It is, however, to be clearly understood, that my invention is not limited to the specific embodiment thereof herein shown and described for purposes of illustration only.

Referring to the drawing, wherein I have illustrated the aforesaid illustrative embodiment of the present invention:

Fig. 1 is a substantially central section 30 of a vanity comprising the aforesaid illustrative embodiment of the present invention;

Fig. 2 is a top plan view of the same with the outer casing partly broken away to make 35 the construction clearer; and

Fig. 3 is an enlarged detail view, partly in section and partly in elevation, showing the hinge construction.

Referring now to the aforesaid illustrative embodiment of the present invention, and more particularly to the drawing illustrating the same, 10 indicates generally the casing or container of the vanity. The casing or container 10 comprises the top or cover portion 11 hinged, as at 12, to the intermediate or ring portion 13 and the removable bottom portion 14. The top portion 11 is preferably provided with the central dome or cover portion 15 and the peripheral or lateral portion 16 which is provided with the beaded upper edge 17 providing a recess 18 for receiving the resilient ring 19 to hold the mirror 20 in place.

For this purpose the resilient ring 19 is 55 provided with the outer peripheral por-

tion 21 which is slightly curvilinear and angularly disposed and with the inner angular mirror receiving ring 22.

The bottom portion 14 comprises a substantially central dome-shaped part 23, the inturned peripheral or lateral portion 24 and the beaded edge 25. Housed within the lower portion 14 is a spiral coil compression spring 26 which, by reason of its force, presses the substantially circular pressure disk 27 to which it is attached by means of the looped portion 27' against the powder which is positioned within the space 28 between the pressure disk 27 and the perforated sifting plate 29. In the position shown in the drawing, the space 28 has little powder in it, the vanity being almost empty of powder. It will, however, be clearly understood that where more powder is put in the space 28, as by removing the bottom member 14 while the vanity is held upside down, the spring 26 will be further compressed so that the pressure disk 27 will be moved downwardly in the bottom member 14 to provide a larger space 28 for the additional powder.

In order to properly position the perforated sifting disk or plate 29, I provide the means, generally designated by reference character 30 and preferably comprising a substantially annular or ring-shaped member having outer inclined peripheral or marginal portion 31 and the inner inclined peripheral or marginal portion 32. The portion 32 is provided with a plurality of lugs 33 which may be passed through perforations 29' in the perforated sifting disk 29 and then bent so as to securely position the member 29. It may here be stated that the disk 29 is provided with the perforations 29'' through which powder is fed for use.

The positioning means 30 are themselves held in place by the upper flange portion 34 with which the ring portion 13 of the container is provided. This ring portion 100 preferably comprises the flange 34, already described, the bearing portion 35 against the bottom of which the perforated disk 29 is held, the inner portion 36, which provides a frictional contact with the lower member 14 for retaining the same in place, and the outer marginal portion 37 in one part of which the hinge 12 is positioned. There is also provided the outer portion 37', so that the ring 13 is in cross section substantially 110

U-shaped. One point of the ring member 13, preferably a point substantially oppositely disposed to the hinge portion 12, is provided with locking means 38 for locking the 5 cover 15 in place.

Referring now to the hinge 12, it will be noted that the same comprises the looped or bent pin-receiving portion 39 which preferably forms an extension of the lower edge 10 of the portion 16 of the cover 15. Held within the space 39' thus provided within the looped portion 39 is the hinge pin 40, the central portion 41 of which is preferably substantially cylindrical so as to provide a 15 proper bearing for the looped portion 39 of the cover 15 as it is opened and shut, while at 42 and 43 the pin 40 is slightly enlarged in one of its cross dimensions, as by being suitably flattened, so to prevent the various 20 parts from being circumferentially displaced with respect to each other. The ends 44 and 45 of the wire or pin 40 are disposed within the ring 13 which is cut away, as indicated at 13', in order to provide for the proper 25 positioning of the portion 39.

The locking means 38, which may be of any desired construction, may, as illustrated, comprise the spring-pressed locking member 46 suitably positioned adjacent the end 30 of the leaf of other suitable spring 47 by means of which, in the closed position of the device, it is pressed into the opening or depression 48 in the member 16. Upon the exertion of the necessary degree of force for 35 lifting the cover 15, in the usual manner, the same may be raised against the action of the spring 47, thus causing the locking member 46 to slip out of the aperture or depression 48 in a manner which will be readily 40 apparent to those skilled in the art to which the present invention relates.

This completes the description of the aforesaid illustrative embodiment of the present invention. It will be noted that 45 same is simple in construction and may be readily and economically fabricated and assembled. In use, the device provides a readily adjustable space for containing the powder in the device under such conditions that as the powder is consumed, the space automatically diminishes in size to maintain the powder under sufficient compression to prevent the same from sifting through the 50 perforated plate except when the powder is desired to be used. The device also provides compact space for containing the powder puff and the mirror, and possesses other advantages in construction and in use which will readily occur to those skilled in the art 55 to which the present invention relates.

What I claim as my invention is—

1. A vanity or the like, comprising, in combination, an open-ended container for powder having a bottom portion and a peripheral flange portion, a surrounding bezel 65

portion, and a cover portion, a perforated powder-sifting plate adjacent the open end of said powder container, a pressure plate within said powder container, and means for pressing said pressure plate toward said perforated powder-sifting plate. 70

2. A vanity or the like, comprising, in combination, an open-ended container for powder having a bottom portion and a peripheral flange portion, a surrounding bezel 75 portion of substantially U-shaped cross-section, and a cover portion, a perforated powder-sifting plate adjacent the open end of said powder container, a pressure plate within said powder container, and means 80 for pressing said pressure plate toward said perforated powder-sifting plate.

3. A vanity or the like, comprising in combination, an open-ended container for powder having a bottom portion and a peripheral flange portion, a surrounding bezel 85 portion of substantially U-shaped cross-section and comprising a central connecting web portion and a plurality of upstanding flange portions, and a cover portion, a perforated powder-sifting plate adjacent the open end of said powder container, a pressure plate within said powder container, and means for pressing said pressure plate toward said 90 perforated powder-sifting plate. 95

4. A vanity or the like, comprising, in combination, an open-ended container for powder having a bottom portion and a peripheral flange portion, a surrounding bezel portion, and a cover portion, a perforated powder-sifting plate adjacent the open end of said powder container, means comprising a substantially ring-shaped member carried by said bezel portion for positioning said perforated powder-sifting plate, a pressure plate within said powder container, and means for pressing said pressure plate toward said perforated powder-sifting plate. 100

5. A vanity or the like, comprising, in combination, an open-ended container for powder having a bottom portion and a peripheral flange portion, a surrounding bezel portion of substantially U-shaped cross-section, and a cover portion, a perforated powder-sifting plate adjacent the open end of said powder container, means comprising a substantially ring-shaped member carried by said bezel portion for positioning said perforated powder-sifting plate, a pressure plate within said powder container, and means for pressing said pressure plate toward said perforated powder-sifting plate. 110

6. A vanity or the like, comprising, in combination, an open-ended container for powder having a bottom portion and a peripheral flange portion, a surrounding bezel portion of substantially U-shaped cross-section and comprising a central connecting web portion and a plurality of upstanding flange portions, and a cover portion, a per-

- forated powder-sifting plate adjacent the open end of said powder container, means comprising a substantially ring-shaped member carried by said bezel portion for 50
- 5 positioning said perforated powder-sifting plate, a pressure plate within said powder container, and means for pressing said pressure plate toward said perforated powder sifting plate.
- 10 7. A vanity or the like, comprising, in combination, an open-ended container for powder, a surrounding bezel portion of substantially U-shaped cross-section, and a hinged cover portion, a perforated powder- 55
- 15 sifting plate adjacent the open end of said powder container, means comprising a substantially ring-shaped member carried by said bezel portion for positioning said perforated powder-sifting plate, a pressure 60
- 20 plate within said powder container, and means comprising a coil expansion spring positioned within said powder container for pressing said pressure plate toward said perforated powder-sifting plate. 65
- 25 8. A vanity or the like, comprising, in combination, an open-ended container for powder, a surrounding bezel portion of substantially U-shaped cross-section and comprising a central connecting web portion 70
- 30 and a plurality of upstanding flange portions, and a hinged cover portion, a perforated powder-sifting plate adjacent the open end of said powder container, a pressure plate within said powder container, and 75
- 35 means comprising a coil expansion spring positioned within said powder container for pressing said pressure plate toward said perforated powder sifting plate. 80
- 40 9. A vanity or the like, comprising, in combination, an open-ended container for powder, a surrounding bezel portion, and a hinged cover portion, a perforated powder- 85
- 45 sifting plate adjacent the open end of said powder container, a pressure plate within said powder container, and means comprising a coil expansion spring positioned within said powder container for pressing said pressure plate toward said perforated powder-sifting plate. 90
- 45
10. A vanity or the like, comprising, in combination, an open-ended container for powder, a surrounding bezel portion of substantially U-shaped cross-section and comprising a central connecting web portion and a plurality of upstanding flange portions, and a hinged cover portion, a perforated powder-sifting plate adjacent the open end of said powder container, means comprising a substantially ring-shaped member carried by said bezel portion for positioning said perforated powder-sifting plate, a pressure plate within said powder container, and means comprising a coil expansion spring positioned within said powder container for pressing said pressure plate toward said perforated powder sifting plate. 95
11. A vanity or the like, comprising, in combination, an open-ended container for powder, a surrounding bezel portion, and a hinged cover portion, a perforated powder-sifting plate adjacent the open end of said powder container, means comprising a substantially ring-shaped member carried by said bezel portion for positioning said perforated powder-sifting plate, a pressure plate within said powder container, and means comprising a coil expansion spring positioned within said powder container for pressing said pressure plate toward said perforated powder-sifting plate. 75
12. A vanity or the like, comprising, in combination, an open-ended container for powder, a surrounding bezel portion of substantially U-shaped cross-section, and a hinged cover portion, a perforated powder-sifting plate adjacent the open end of said powder container, a pressure plate within said powder container, and means comprising a coil expansion spring positioned within said powder container for pressing said pressure plate toward said perforated powder-sifting plate. 85
- In testimony whereof, I have signed my name to this specification this 4th day of August, 1927. 95

WALTER PORANSKI.
